UNITED STATES PATENT OFFICE.

ROBERT H. SPENCER, OF TURLOCK, CALIFORNIA.

RAILROAD-TIE.

1,349,171.

Specification of Letters Patent. Patented Aug. 10, 1920.

Application filed October 15, 1919. Serial No. 330,885.

To all whom it may concern:

Be it known that I, ROBERT H. SPENCER, a citizen of the United States, residing at Turlock, in the county of Stanislaus, State of California, have invented certain new and useful Improvements in Railroad-Ties; and I do declare the following to be a full, clear, and exact description of the same, reference being had to the accompanying drawings, 10 and to the characters of reference marked thereon, which form a part of this application.

This invention relates to improvements in railroad ties, the principal object of the invention being to produce a tie which will be non-vibrating, non-breakable, and practically fireproof.

Another object is to produce a tie which as a whole will be practically everlasting, 20 and in which such destructible parts as are used may be easily replaced without the necessity of taking up the tie or replacing the same as a whole.

A third object is to so construct the tie that when laid and surrounded with ballast it will not be liable to side slippage or lateral displacement.

If wood is used in the construction of the tie, only short lengths are needed, thus enabling me to utilize stock which would otherwise be of no value, and which may naturally be obtained at a much lower cost than the standard lengths at present used, especially with the increasing scarcity of lumber.

A further object of the invention is to produce a simple and inexpensive device and yet one which will be exceedingly effective for the purposes for which it is designed.

These objects I accomplish by means of such structure and relative arrangement of parts as will fully appear by a perusal of the following specification and claim.

In the drawings similar characters of reference indicate corresponding parts in the several views.

Figure 1 is a top plan view of my improved tie, showing the rails positioned thereon.

Fig. 2 is a side elevation of the same.
Fig. 3 is a cross section taken on a line 3-3 of Fig. 1.
Fig. 4 is a similar view taken on a line 4-4 of Fig. 1.
Fig. 5 is a view similar to Fig. 3, but

showing the rail-bearing portion composed of two different materials.

Referring now more particularly to the characters of reference on the drawings the numerals 1 and 1^a denote a pair of channel shaped members open at the top, and constructed of pressed steel, galvanized or plain, each being substantially half the standard length of a tie. The adjacent ends 2 and 2^a of the members 1 and 1^a overlap each other 60 for a certain distance, while at this point the bottom portion 3 of each is cut lengthwise and centrally thereof as at 4 and the cut portions then bent upward to form ears 5 and 5^a on each of the members 1 and 1^a 70 respectively, which overlap each other inside the overlapping ends 2 and 2^a.

A bolt 6 passes through the ends 2 and 2^a and the ears 5 and 5^a thus firmly but flexibly connecting the two channels 1 and 1^a together.

The outer ends of these channels are each filled with a solid block of material 7 preferably wood, which extends a suitable distance on either side of the line of the rails 8 80 which are spiked thereon, and slightly above the sides of the channels. These blocks are secured in place in the channel members by means of spikes or lag screws 9.

If desired, in order to economize on wood, 85 or to make a heavier tie, the channels may be partially filled with concrete 10 or similar material, which may be poured therein and secured thereto by anchor bolts 11.

Small blocks of wood 12 would also be 90 set into the concrete filling in alignment with the rails 8 and for the same purpose as the blocks 7, wood being the best material for the purpose, as it absorbs vibration and is elastic or spongy compared with steel or concrete.

When the ties are laid in place on the road bed, and the usual crushed rock or gravel ballast tamped thereabout, some of the latter will be forced up into the open space formed 100 by the cutting away of the bottoms of the channels. This will materially aid in keeping the ties from moving sidewise and warping the track.

Also the fact that the two halves of the 105 tie are hinged together on a horizontal line tends to lessen and destroy vibration, as there is a certain amount of flexibility or give between the two rails.

From the foregoing description it will be 110

readily seen that I have produced such a device as substantially fulfills the object of the invention as set forth herein.

While this specification sets forth in detail the present and preferred construction of the device still in practice such deviations from such detail may be resorted to as do not form a departure from the spirit of the invention, as defined by the appended claim.

Having thus described my invention, what I claim as new and useful and desire to secure by Letters Patent is:

A railroad tie comprising a pair of metal channels positioned end to end, the bottoms

of said channels being cut for a certain distance from the adjacent ends and turned up to form ears, the ears and ends on one channel interlocking with those on the other, a pivotal pin through such ends and ears, and blocks secured in the channels, such blocks terminating short of the hinged ends and adapted to receive the rails thereon.

In testimony whereof I affix my signature in presence of two witnesses.

ROBERT H. SPENCER.
